UNITED STATES PATENT OFFICE.

FRANZ GUNDEL, OF JERSEY CITY, NEW JERSEY.

COLLAPSIBLE UMBRELLA FRAME.

Application filed May 26, 1928. Serial No. 280,716.

My invention relates to collapsible umbrellas, which are known in various forms of execution, generally involving the principle of lazy tongs. Such umbrellas mostly have the disadvantage of complication and have therefore not gained popularity with the public; whereas there are some which are simpler in construction, they do not collapse to so small a fraction of their full size as to warrant their preference to the ordinary umbrella construction.

In developing my improvement I have tried to overcome the handicaps of the construction of such umbrellas, and the objects of my invention are therefore, a collapsible umbrella frame which, first, supports the fabric in the same way as an ordinary umbrella; second, has the ribs attached to the fabric in the manner of the ordinary umbrella; third, does not comprise more parts than the ordinary umbrella; fourth, does not have lazy tongs, nor joints crossing each other; fifth, folds the fabric upon itself at one point only, and does not allow the fabric to be clamped or mutilated by the folding; sixth, has a collapsible handle which is frictionally held in the closed and partly opened positions, and firmly secured in the fully open position; seventh, does not involve catches to be manipulated for the opening and closing, except for the fully open position of the frame.

I attain these objects by the mechanism illustrated in the accompanying drawings, in which:

Figure 1 is a sectioned side view of part of my invention showing the fully opened handle as well as a rib and the corresponding supporting means in the open position.

Figure 2 shows a similar view, in which the frame and the telescopic handle are almost completely folded together.

Figure 3 shows a sectioned, sectional view of one of the joints on the handle.

Figure 4 shows a side view of one of the novel joints I use in my umbrella, together with the ends of the ribs hinged together in that joint.

Figure 5 shows the end view of another joint I use in the execution of my invention.

In Figure 1 the ribs 6 are hinged to the end of the umbrella in the manner usually employed for that purpose. The joint at 7, between the sections 8 and 9, is similar to the joint in which section 6 hinges upon the end of the umbrella. But the joint, 10 is

really a doubled joint as detailed in Figure 4. The rib sections 6 and 8 are hinged at a certain distance apart from each other, in pivots 12 and 13, in the U-shaped trough 11. When the sections 7 and 8 are folded together, in the manner indicated in Figure 2, there is a certain space between them at their point of folding, i. e., at joint 10, for the fabric of the umbrella.

Whereas the three rib sections 6, 8 and 9 extend in a substantially straight line when the umbrella is opened, the supporting strut and web sections 14, 15 and 16 are arranged next to those rib sections, displaced for the distance of their own width to the side. Whereas the joint 17 is similar to that at 7, the joints at 18, 19 and 20 are constructed in the way shown in Figure 5.

For the illustration of that joint I refer to the joint at 20, between the rib 9 and the web 16. There is a clamp 21, fastened upon the rib 9 by the rivet 22, and upon the end of that rivet the web 16 is hinged. The joints 18 and 19 being constructed in the same manner, it is clear that in folding up the umbrella the webs 15 and 16 fold up next to the webs 6, 8, and 9; and again the strut 14 folds up next to the web 15, so that in the closed position of the umbrella the ribs 6, 8 and 9, the webs 15 and 16, and the strut 14, are respectively aligned next to each other, in clockwise direction, when seen from the top of the umbrella frame.

The other end of strut 14 is hinged upon the sleeve 23, which is slidable on the tube 24, in a joint 25 similar to the joint in which rib sections 6 are hinged upon the end of the tube 24. The sleeve 23 may be set at any point upon the tube by the knurled head screw 26. That screw is mounted in a small bridge 27 upon the sleeve and exerts, when tightened, a pressure upon the sleeve by pressing the sleeve upon the tube so as to hold the sleeve in a fixed position. There is a protrusion 28 around tube 24 which serves to stop the sleeve 23, when it has been moved along the tube 24 to the fully open position of the frame. It may be produced either by spinning out the tube at that point or by fastening a ring upon it.

The smallest section 29 of the telescopic handle is fastened to the top of the umbrella frame on the inside of tube 24. Over that section, and respectively over each other, are slidably arranged the handle sections 30, 31 and 32. The last one of these carries the

knob 33. Where these sections, respectively terminate inside of the next larger sections, their ends 34 are flared out, so as to slide upon the inside of these next larger sections, 5 because the outside diameters of the small sections are slightly smaller than the inside diameters of the next larger sections in which they slide. Therefore, for the same purpose, the ends 35 are spun in, to slidably 10 fit upon the outside of the sections telescoped into them. Near that end 35 of the sections is fastened to them, on their insides, a flat spring 36, which assumes the position of Figures 1 and 3, when the umbrella 15 is fully open. There are slots 37 of the width of those flat springs 36 in the ends of the sections, extending so far up from the ends 34 as to allow the springs 36 to assume the positions of Figures 1 and 3.

20 In these particular positions, the flared ends 34 on the inner sections rest against notches 38, on the outer sections, preventing the handle from being pulled out beyond that point.

25 The second smallest section 30 of the handle carries a collar 39 on the outside near its end. This collar, on its outside, is slidable on the inside of tube 24.

The length of the springs 36, as chosen 30 in the drawings, is of course arbitrary. Under certain conditions, preference is given to a spring which is fastened on the inside of the tube at one end, similar to the construction shown, but the spring extends 35 through the whole length of the tube, and is gently curved so that in the open position it extends from the upper right hand corner on the inside of the tube to its lower left hand corner. A spring of this type 40 offers an even friction throughout, in all the positions in which the telescopic handle may be used.

In certain details the drawings show the parts larger than they actually are. So, for 45 instance, the set screw 26 on the bridge 27 may be smaller, and placed between adjacent ribs when they are folded up, and the tube 29 is shortened up correspondingly, so that the umbrella when folded up, will 50 not be greater in length than the longest of the rib sections 9. A knob of the kind shown, 33, may also be provided with a groove on the side facing the umbrella so that, when the section 32 is completely 55 pushed into the outer tube, that hollow part in the knob extends over the sleeve and also over the ribs and webs lying on the tube and said sleeve, holding them firmly together, while the umbrella is folded up and 60 not in use.

The above description shows that the principles of my invention are different from those normally involved in the construction 65 of collapsible umbrellas. Whereas such other constructions usually provide for a

frame, which when opened up, is self-supporting and stable, I avail myself to a great extent, of the tension exerted by the fabric cover to stabilize the umbrella in the open position. A frame, like the one shown in Fig. 1, is absolutely unstable, according to the well-known rule that a geometrical assembly of links, jointed at all corners of the geometrical figure, cannot be stable if it has more than three corners. In my frame there is one geometrical figure, with one corner at the point in which the rib 6 is hinged upon the umbrella staff, joints 18, 19 and 25 representing three additional corners. The other geometrical figure contained in my frame, with joints 7, 10, 18, 17 and 20 has even five corners. However, by a balance of the length of the various sections I obtain the desired stability of my frame, as soon as the fabric cover is attached over it: The section 8 is freely suspended between the sections 6 and 9. These two latter sections have the web sections 15 and 16 attached to them in pivots 18 and 20; the joint 17 between the web sections being pushed toward the rib sections by the pressure of strut 14, the parts of the rib sections between points 18 and 20 are under a tension, away from each other, whereas the stresses in webs 15 and 16 are compressive, at least as far as 16 is concerned, whereas there is an additional bending stress in the web 15, owing to the pressure exerted upon it by the strut 14 at the joint 19. It is evident that in the light of these considerations, I make certain sections different in cross sections from the others according to the stresses to which they are exposed, cross sections in the drawings being chosen of the same kind throughout, because I use the drawings mainly to explain the principle of my invention.

Ribs and webs of various cross sections are used for umbrella construction. In the light of the preceding paragraph, I may choose stronger or weaker cross sections for the various sections of my frame. The simple joints, shown at 7 and 17 may be readily executed in the shape ordinarily used with ribs of a U-shaped cross section. But I give to the ribs, near these joints, a slight curvature, so that they may fold up on top of and parallel to each other.

I may, of course, resort to means which prevent the sleeve 23 from turning on 24. But I have found that the connecting rib-web-and strut-sections offer sufficient means to guide the sleeve in its motion along the tube 24. I may of course provide notches in ring 28, into which fit the web or rib sections when folded up, offering an additional means to firmly locate all parts when collapsed.

I claim:

1. In a collapsible umbrella of the kind described in combination with a tube, a

handle telescopically collapsing into said tube, a sleeve slidable upon said tube, ribs hinged upon said tube—a plurality of jointed sections making up each one of said ribs, 5 supports, each comprising two webs jointed together and hinged in their free ends, respectively, upon the first and last one of said sections making up said ribs, and struts operatively connected to said sleeve at one end 10 and hinged in their other ends upon the said supports.

2. In a collapsible umbrella of the kind described in combination with a tube, a handle telescopically collapsing into said tube, a sleeve slidable upon said tube, ribs hinged upon said tube—a plurality of jointed sections making up each one of said ribs, 15 supports, each comprising two webs jointed together and hinged in their free ends, respectively, upon and laterally joining the first and last one of said sections making up said ribs, and struts operatively connected to said sleeve at one end and hinged in their other ends upon and laterally adjoining the 20 said supports.

3. In a collapsible umbrella of the kind described in combination with a tube, jointed ribs hinged upon said tube, a sleeve slidable upon said tube and operatively connected to 25 said jointed ribs—a bridge upon said sleeve and a set screw in said bridge in abutment upon the outside of said tube.

4. In a collapsible umbrella of the kind described in combination with a tube, jointed

ribs hinged upon said tube, a sleeve slidable 35 upon said tube and operatively connected to said jointed ribs—an arbor mounted in the center of said tube, a plurality of telescopic tubes slidable upon said arbor and upon each other, successively, and fitting into said tube, 40 and a collar fastened upon the end of the smallest one of said telescopic tubes and slidable in said tube.

5. In a collapsible umbrella of the kind described in combination with a tube, jointed 45 ribs hinged upon said tube, a sleeve slidable upon said tube and operatively connected to said jointed ribs—an arbor mounted in the center of said tube, a plurality of telescopic tubes successively clearing said arbor and each 50 other and fitting into said tube, an enlargement on the free end of said arbor slidably fitting the smallest ones of said telescopic tubes, enlargements on the corresponding ends of the telescopic tubes, slidably fitting, 55 successively, the insides of the next larger ones of said telescopic tubes, contractions on the other ends of said telescopic tubes respectively slidable upon the arbor and the successively smaller ones of said telescopic tubes, 60 tensile members on the inside of said telescopic tubes frictionally engaging, respectively, said arbor and the successively smaller ones of said telescopic tubes.

Signed at New York in the county and 65 State of New York this 23rd day of May, A. D. 1928.

FRANZ GUNDEL.
